UNITED STATES PATENT OFFICE

136,259

DESIGN FOR A LOCOMOTIVE BODY

Raymond G. F. Loewy, Sands Point, N. Y., assignor to The Pennsylvania Railroad Company, Philadelphia, Pa., a corporation of Pennsylvania

Application April 10, 1943, Serial No. 109,947

Term of patent 14 years

To all whom it may concern:

Be it known that I, Raymond G. F. Loewy, a citizen of the United States of America, residing at Sands Point, in the county of Nassau and State of New York, have invented a new, original, and ornamental Design for a Locomotive Body, of which the following is a specification, reference being had to the accompanying drawings, forming part thereof.

The present application is a continuation-in-part of my co-pending application Serial Number D-105,537, filed January 31, 1942.

In the drawings, Fig. 1 is a side perspective view of a locomotive body showing my new design.

Fig. 2 is a side elevational view of the locomotive body.

Figs. 3 and 4 taken together show the locomotive body in plan.

Fig. 5 is a front elevational view of the locomotive body; and

Fig. 6 is a diagrammatic outline of a vertical section taken through the rear end portion thereof.

The opposite side of the locomotive body is identical with the side which is shown in Figs. 1 and 2.

I claim:

The ornamental design for a locomotive body, as shown and described.

RAYMOND G. F. LOEWY.
